UNITED STATES PATENT OFFICE.

ERIK NORBERG, OF LACKAWANNA, NEW YORK.

AUTO TRIPLE-EXPANSION ENGINE.

Application filed August 6, 1927. Serial No. 211,123.

My present invention has reference to steam engines, and my object is the provision of a triple expansion engine of this type in which the full force of the steam pressure is expended in projecting the pistons to the full length of their stroke and returning the pistons to initial position to be again acted on by live steam at the time of exhaust of the steam which initially influenced the 10 pistons and whereby a smooth and rapid reciprocation of the pistons is produced with a minimum amount of steam pressure.

A further object is the novel construction of pistons and their arrangement in cylinders of a particular formation, together with valves in the pistons and means for automatically opening and closing such valves in proper timed relation to permit of the full force of steam being directed against 20 the pistons and exhausted through the openings that provide the valve seats.

The invention will be fully and comprehensively understood from a consideration of the following detailed description when read 25 in connection with the accompanying drawings which form part of the application, with the understanding, however, that the improvement is capable of extended application and is not confined to the exact showing 30 of the drawings nor to the precise construction described and, therefore, such changes and modifications may be made therefrom as do not affect the spirit of the invention nor exceed the scope thereof as expressed 35 in the appended claims.

In the drawings:

Figure 1 is a top plan view of an engine in accordance with this invention.

Figure 2 is a side elevation thereof.

Figure 3 is a somewhat enlarged sectional view approximately on the line 3—3 of Figure 2.

Figure 4 is a similar view but showing the pistons in a different position from that disclosed by Figure 1.

Figure 5 is a transverse sectional view approximately on the line 5—5 of Figure 6.

Figure 6 is a sectional view approximately on the line 6—6 of Figure 5.

Figure 7 is an enlarged sectional view approximately on the line 7—7 of Figure 4.

Figure 8 is a detailed sectional view.

The engine is supported upon a suitable base and, in the construction illustrated includes a central or intermediate head 1 and end heads 2. The heads 1 and 2 are con-

nected by oppositely directed cylinders 3 which provide, with the heads, the engine casing.

Journaled in suitable bearings or standards arising from the base or support 4 for the engine there is a shaft 5 having belt and fly wheels thereon and also having an intermediate crank portion 6 and end crank portions 7, respectively. In addition to the 60 cranks the shaft 5 has fixed thereon a cam wheel 8 surrounded by a cam strap 9 to which is fixed one end of a rod 10, the said rod being directed toward the head 1, and being connected to the cranked end 11 of the shaft 12 for revoluble plug valve 13 that is seated in the head 1. Preferably a spring 14 is arranged around the rod or stem 12 of the valve 13 and exerts a pressure between the valve and the portion of the head through 70 which the stem passes so that the valve 13 is properly sustained on its seat. The valve 13 is provided with two spaced ports 14' and 15, respectively designed to align with ports 16 and 17, in the steam inlet passage 18 in 80 the head 1. The ports 16 and 17 communicate with transversely arranged round and somewhat enlarged openings 19 that pass through the head 1. The valve construction and its operation is ordinary, inasmuch as the same is employed upon various 85 types of steam engines, especially that of the Corliss type.

The cranks 6 and 7 of the shaft 3 have connected thereto pitmen 20 and 21—21, 90 respectively, and all of these pitmen have their free ends pivotally connected to slideable cross heads 22 that carry rods 23 and 24—24, respectively.

The rod 23 passes through a packing box 95 and likewise through a depression or pocket 25 in the head 2 of the engine casing which is arranged next to the crank shaft and is connected, preferably through the medium of a plate 26 to the head 27 of a hollow 100 cylindrical piston 28. Secured to the plate 26 and to the head 27 of the hollow piston 28 there are a pair of parallel rods 29. These rods freely pass through the openings 19 in the engine head 1, (leaving an ample 105 space for the passage of steam through said ports or openings 19) and are secured to a piston 30 that is arranged at one side of the head 1 but does not directly contact therewith. The piston 30 is slideable through 110 a cylinder 31 that has one end fixed to one side of the head 1. A second piston 33,

similar to the piston 30, is arranged in the engine casing at the opposite side of the head 1. This piston 33, has secured centrally thereon the reduced ends of rods 34. These rods are arranged centrally and right angularly with respect to the rods 29 and are passed through suitable guide openings in the engine head 1. The rods 34 are directed centrally through the cylinder 31 and 10 are connected to the head of a hollow piston 35 similar to the piston 28. The inner face of the head of the hollow piston 35 has an annular depression through which pass headed bolts 36 that secure the outer face of the 15 piston head to a rod 37 that passes through an opening closed by a packing box in the outer head 2 of the engine. The rod 37 has secured thereon a cross bar 38, and to the ends of this bar the rods 24 are also secured. The 20 rods 24 pass through suitable guides 39 on the sides of the head 1. The piston 33 is arranged for slidable movement in a cylinder 40 secured on the side of the head 1 opposite the cylinder 31, and the rods 29 25 pass through suitable guide openings in the said piston 33.

The cylinders or chambers 31 and 40 have their inner faces, at their outer ends formed with equidistantly spaced somewhat elongated depressions providing steam outlet 30 passages 41. The cylinders 31 and 40, at their said outer ends are formed with outwardly extending annular beads or flanges 42, respectively. In these beads or flanges 35 42 there are outwardly projected spring influenced contact elements in the nature of headed pins 43, the purpose of which will be presently apparent.

The hollow pistons 28 and 35 are arranged 40 for slidable movement over the flanged or beaded ends of the cylinders 31 and 40. The heads of the pistons 28 and 35 are formed with series of circumferentially arranged round openings 45 whose inner walls 45 provide seats for the heads of valve 46 which are normally unseated by springs 47. The heads of the hollow pistons 28 and 35 extend a suitable distance beyond the cylindrical body portions of said pistons and bear 50 against the inner walls of the engine cylinders 3. These flanged or beaded portions of the hollow pistons have a series of equidistantly arranged openings 47' whose outer walls provide seats for valves 48, which are 55 normally unseated by springs 49. The engine heads 2, in a line with the valves 48, have inwardly extending spring influenced pins 50 which are designed to seat the valves when the hollow pistons are moved 60 next to the heads of the engine. The engine cylinders 3, near their heads 2 have depressions 51 providing steam passages, and the heads of the hollow pistons have peripheral angle ports 52 which communicate 65 with the hollow body of the pistons and with

the passages 51 when the said hollow pistons are moved to the limit of their outward strokes.

The pistons 30 and 33 are also provided with round openings whose inner walls provide seats for normally open spring influenced valves 53 while the head 1 has arranged therein spring influenced pins 55 that are in the path of contact with the valves 53 to close such valves. Preferably 75 all of the valves and the contacts therefor have their stems guided through spiders 56 whose construction is best illustrated by Figure 7 of the drawings.

The steam intake 18 is, of course, connected with the steam chest, and when the shaft 5 is turned so that the cam 8 will open the valve 13, steam will be directed through the passages 17 and openings 19 to act on the pistons 30 and 33. Of course, 80 the valve 13 is only temporarily opened and the steam will influence the pistons 30 and 33 to move the same outwardly through the cylinders 31 and 40. As these pistons are connected to the hollow pistons 28 and 35 by 85 the rods 29 and 34 they will draw the said hollow pistons over the said cylinders toward the engine head 1. The full force of the steam is directed against the pistons 30 and 33 and, therefore, these pistons may be 90 termed the high pressure pistons. When the steam has acted upon the high pressure pistons 30 and 33 to force the same into their full outward strokes the heads of the pistons 28 and 35 will have their valves 46 contacted by the pins 43 so that these valves 95 will be closed. Also at their full outward stroke the steam passes from the cylinders 31 and 40 through the passages 41 into the 100 hollow pistons 28 and 35. The steam pressure in the hollow pistons and in the cylinders 40 and 31, is now equalized and the steam in the cylinders 31 and 40 will automatically unseat the valves 53. The force 105 of steam in the hollow pistons will move the same in the direction of the heads 2 of the engine and return the high pressure pistons to their initial position where the valves 53 will be seated by contact with the pins 55 and immediately thereafter valve 110 115 115 120 125 130 135 140 145 150 155 160 165 170 175 180 185 190 195 200 205 210 215 220 225 230 235 240 245 250 255 260 265 of the head 1, so that after the said hollow pistons have moved away from the stop pins the valves 48 will be opened by their springs 49 and the spent steam will find an exhaust through the engine cylinders 3 and through an exhaust port 57 which is preferably located in the lower portion of the head 1.

The pistons will be moved at one stroke by both high and low pressure and by intermediate pressure on the other stroke. The construction prevents any back pressure of steam so that the pistons receive the full benefit of such steam. It is to be noted that only the inlet valve is operated by mechanism attached to the crank shaft and that all of the other valves are automatic in their action.

The engine is of a comparatively simple structure and includes only a few parts which are not liable to disassociation, disorder or breakage. The construction provides a high power engine in which only a minimum amount of steam is employed and in which all of the energy is utilized. The improvement is, of course, susceptible to changes and modifications.

Having described the invention, I claim:

1. A triple expansion steam engine, comprising, in combination, an intermediate head, end heads, cylinders connecting said heads and smaller and shorter cylinders in the main cylinder secured to and extending in opposite directions from the intermediate head, a high pressure piston in each of the inner cylinders, hollow pistons movable over the inner cylinders, oppositely directed rods guided through the intermediate head and high pressure pistons and connecting the respective high pressure pistons with the hollow pistons, valve controlled means for admitting steam through the intermediate head to act on the high pressure pistons, means for directing steam from the high pressure pistons into the hollow pistons on the end of the outward stroke of said high pressure pistons and the end of the inward stroke of the hollow pistons to force the hollow and high pressure pistons away from each other, means for directing the steam from the hollow pistons to compress the said steam between said pistons and the end heads of the engines to assist in the return stroke of the hollow pistons and means for exhausting such steam when live steam is again admitted against the high pressure pistons.

2. A triple expansion steam engine, comprising, in combination, an engine casing made up of an intermediate head, end heads and cylinders connecting said heads, smaller and shorter cylinders in the main cylinders secured to and extending in opposite directions from the intermediate head, a high pressure piston in each of the inner cylinders, hollow pistons movable over the inner cylinders, oppositely directed rods guided

through the intermediate head and high pressure pistons and connecting the respective high pressure pistons with the hollow pistons, valve controlled means for admitting steam into the inner cylinders to act on the high pressure pistons, means for equalizing the steam pressure between all the pistons when the high pressure pistons are at the limit of their outward stroke and the hollow pistons at the limit of their inward stroke and to move such pistons in their opposite strokes, means for directing steam through the heads of the hollow pistons against the end heads of the engine casing when the hollow pistons are at the limit of their outward stroke and the high pressure pistons almost at the limit of their inward stroke, and whereby to compress such steam to assist in the return inward stroke of the hollow pistons just prior to the admission of live steam to the inner cylinders and the pistons therein and means for exhausting the spent steam.

3. The combination, a casing, comprising an intermediate head, end heads and cylinders connecting the heads, shorter and smaller cylinders secured to the opposite faces of the intermediate head, a piston in each of said inner cylinders, hollow pistons movable on the inner cylinders and having heads guided in the main cylinders, oppositely directed rods secured to the first mentioned pistons, guided through the intermediate head and through said pistons and connecting the heads of the respective hollow pistons therewith, rods connected to said hollow pistons and guided through the end heads of the engine, a cross bar on one of said rods, a cranked shaft, pitmen thereon and rods connecting the pitmen with the cross bar and with the rod of the second hollow piston, means actuated by the crank shaft for admitting steam into the inner cylinders to act on the pistons therein, means for equalizing the steam pressure between all of the pistons when the first mentioned pistons are at the limit of their outward stroke and the hollow pistons at the limit of their inward stroke to move said pistons to their opposite strokes, means for directing steam through the heads of the hollow pistons against the end heads of the engine casing, when the hollow pistons are at the limit of their outward stroke and the first mentioned pistons almost at the limit of their inward strokes and whereby to compress such steam to assist the return inward stroke of the hollow pistons just prior to the admission of steam to the inner cylinders and means for exhausting the spent steam.

4. In a steam engine, the combination, a cylindrical casing having an intermediate and end heads, inner cylinders secured to the sides of the intermediate head having inner depressions adjacent to the outer ends thereof and having their said outer ends

flanged, outwardly projected spring pressed pins on the flanges, a piston in each of the inner cylinders, having openings therethrough and spring influenced normally open valves for closing said openings, spring pressed pins on the intermediate head contactable with said valves to close the same, oppositely directed rods secured to said pistons, directed through the intermediate head and the respective pistons, hollow pistons guided on the flanges of the cylinders, and to whose heads the rods are connected, said hollow heads having inwardly opening normally unseated spring influenced valves in the path of contact with the pins on the flanges of the cylinders and having other outwardly opening spring influenced valves, disposed adjacent to the periphery of the heads of said pistons, said heads having angle ports establishing communication between the hollow pistons and the periph-

ery of the heads, the engine cylinders having steam passages to communicate with said ports when the hollow pistons are in one position, the end heads of the engine having 25 spring pressed pins in the path of contact with the last mentioned valves of the hollow pistons, a rotatable valve in the intermediate head of the engine for admitting steam into the intermediate cylinders to act on the pistons therein, rods connected to the heads of the hollow pistons and guided through the engine heads, a crank shaft, pitmen connected therewith, rods connecting the pitmen with the last mentioned rods of the hollow pistons, and means actuated by the turning of the crank shaft for operating the steam inlet valve, all as and for the purpose set forth.

In testimony whereof I affix my signature.

ERIK NORBERG.
